Assistant Examiner—Mary Ann Calabrese

(57) **CLAIM**

What is claimed is an ornamental design for a mobile device label with negative image feature, as shown and described.

DESCRIPTION

FIG. 1 is a top plan view of the mobile device label with negative image feature, showing my new design; having a decorative edge and a transparent film covering

FIG. 2 is a top plan view of a mobile device label with negative image feature shown applied to a mobile device;

FIG. 3 is a top plan view of a mobile device label with negative image feature shown applied in an alternative manner to a mobile device; and,

FIG. 4 is a top perspective view of a mobile device label with negative image feature shown applied to a mobile device.

In the drawings, the broken lines in FIG. 1 define the boundaries of the claimed design. The broken lines showing of the mobile device in FIGS. 2-4 illustrates environmental structure forming no part of the claim.
